Patented Oct. 26, 1971

222,474

COAXIAL SWITCH

John R. Thompson, North Hollywood, Calif., assignor to
Electronic Industrial Engineering, Inc., North Holly-
wood, Calif.

Filed Aug. 26, 1970, Ser. No. 24,703

Term of patent 14 years

Int. Cl. D13—03

U.S. Cl. D26—13

FIG. 1.

FIG. 2.

FIG. 3.

FIG. 4.

FIG. 5.

FIG. 6.

FIG. 1 is an isometric view on a slightly reduced scale of a coaxial switch embodying my new design;

FIG. 2 is a front elevational view of the same;

FIG. 3 is a side elevational view of the same, the opposite side being identical;

FIG. 4 is a rear elevational view of the same;

FIG. 5 is a top plan view of the same;

FIG. 6 is a bottom plan view of the same.

The broken lines are for illustrative purposes only.

I claim:

The ornamental design for a coaxial switch, substantially as shown and described.
